Primary Examiner — Jennifer L Rempfer*Assistant Examiner* — Emily A Caven*(74) Attorney, Agent, or Firm* — Passe Intellectual Property; James G Passe(57) **CLAIM**

The ornamental design for a cat tower, as shown and described.

DESCRIPTION

FIG. 1 is a front view of a cat tower showing my design; FIG. 2 is a left perspective view thereof; FIG. 3 is a right perspective view thereof; FIG. 4 is a top view thereof; and, FIG. 5 is a bottom view thereof.

In the drawings, the broken lines depict portions of the cat tower that form no part of the claimed design.
